Primary Examiner—Carol Rademaker(74) *Attorney, Agent, or Firm*—Ellen Plotkin(57) **CLAIM**

The ornamental design for a squeezable package with cap, as shown and described.

DESCRIPTION

FIG. 1 is a top, front, and right side perspective view of a squeezable package with cap;

FIG. 2 is a front elevational view thereof;

FIG. 3 is a right side elevational view thereof;

FIG. 4 is a back elevational view thereof; and,

FIG. 5 is a top plan view thereof.

The claimed squeezable package is used to store a product, such as a spread, dressing or savory food, and could rest either right side up or upside down on a flat surface.
